RAZOR AND BLADE DISPENSER THEREFOR

Paul Polynice, Southampton, N. Y.

Application June 16, 1949, Serial No. 99,429

1 Claim. (Cl. 30—40)

1

My invention relates to an improved safety-type razor and a dispenser for inserting blades in said razor. My invention is particularly adapted to be used with double-edged blades.

In my invention, I split the transverse walls of the razor blade chamber longitudinally to divide it into two portions. These chamber portions are normally held together by spring action so that they frictionally engage the side cutting edges of a blade positioned in the chamber and thereby prevent lateral movement of said blade and inhibit longitudinal movement thereof.

I provide the dispenser with a boss on one end thereof. This boss may be releasably, but securely, interfitted with one end of the razor and serves as wedge means to spread the blade chamber portions. As a result, the frictional engagement of the side edges of the blade is relaxed, and a new blade dispensed from the dispenser may readily be inserted into the chamber thereby ejecting the old blade.

I thus provide an economically constructed and easily operated razor-dispenser unit. The razor is preferably used with double-edged blades, and new blades may be readily inserted therein by means of the dispenser.

Other objects and advantages of my invention will become apparent in the following description and in the annexed drawings, in which a preferred embodiment is shown.

In the drawings:

Fig. 1 is a top plan view of the razor and the dispenser, showing the same detached from each other;

Fig. 2 is a view similar to Fig. 1, showing the dispenser attached to the razor. The broken lines show the positions of the slider handle and the old blade in the razor when said slider handle is moved part way toward ejecting position;

Fig. 3 is a section on the line 3—3 of Fig. 2;

Fig. 4 is a view similar to Fig. 3 showing the positions of the parts while the slider is being moved to eject the used razor blade;

Fig. 5 is a view similar to Figs. 3 and 4, showing the slider returned to its initial position after the used blade has been ejected from the razor and a new blade inserted;

Fig. 6 is a section on the line 6—6 of Fig. 5;

Fig. 7 is a rear elevation of the dispenser; and

Fig. 8 is a front elevation of the razor. The front end of the dispenser is adapted to engage the rear end of the razor.

Solely for the convenience in description, I define the end of razor R shown in Fig. 8 as the front end thereof, and I define the end of dis-

2

penser D shown in Fig. 7 as the rear end thereof.

Referring to the drawings in detail, it is seen that I provide a razor R whose blade chamber is divided into chamber portions M and N by means of slits 13 which respectively extend the entire length of respective upper transverse wall 15, 15 and lower transverse wall 16, 16. Side walls 19 of this blade chamber M, N are respectively connected by leg members 10 to handle 11, and I provide suitable spring means 12 to urge these legs 10 toward each other. As a result, walls 19 normally frictionally engage the side edges of a blade B positioned in chamber M, N and prevent lateral movement and hamper longitudinal movement of said blade B.

I also provide a dispenser D which has a boss 27 formed on the rear end thereof. I form the front portion of razor R, as well as this boss 27, in such a manner that they may be releasably, but securely, interfitted together. Boss 27 serves to wedge walls 19 apart and thereby sufficiently relax the frictional engagement of the side edges of blade B to facilitate longitudinal movement thereof.

Dispenser D is adapted to dispense a blade B' longitudinally through slot 23 in the rear thereof.

When razor R and dispenser D are interfitted, this blade B' is so positioned that it enters blade chamber M, N as it is dispensed. As the dispensing action continues, and because walls 19 are maintained in spread position, blade B' replaces blade B in chamber M, N and blade B is ejected.

Blade holding means of razor

I provide razor R with a blade chamber M, N which is approximately the size of the preferably double-edged blade B which I provide. This blade B may be inserted and ejected longitudinally from this chamber M, N but is normally substantially free from other movement. Blade B is optionally tapered at its ends to facilitate its insertion in chamber M, N.

Chamber M, N comprises respective substantially parallel upper and lower transverse walls 15, 15 and 16, 16, which are separated by a distance slightly greater than the thickness of blade B, whereby they allow only slight vertical play of said blade B but do not hamper longitudinal movement thereof. These walls 15, 15 and 16, 16 are split along their entire lengths, by means of respective slits 13, into respective upper wall members 15 and lower wall members 16.

Chamber M, N is open at each end and has

side walls 14 which extend below wall 16, 16 and in front of walls 15, 15 and 16, 16. Chamber portions M and N respectively comprise a respective wall 14, together with the members 15 and 16 attached thereto.

A leg member 10 is attached to each side wall 14 and extends downwardly. These legs 10 converge toward each other and are secured inside hollow handle 11. Legs 10 are slightly resilient, and I provide spring means 12 which normally urge said legs 10 toward each other. Spring 12 is made of spring steel and is preferably V-shaped, its legs being respectively mounted along the inside surfaces of respective legs 10 and its base being located within handle 11. Optionally, any other suitable construction may be utilized for spring 12.

I provide longitudinal cut-outs 15a which respectively extend from points adjacent the front end of razor R to points adjacent the rear end thereof and are respectively located in the outer portions of wall members 15 and upper portions of walls 19. These cut-outs 15a expose most of the side cutting edges of a blade B disposed in chamber M, N. The end portions of walls 19, which have not been cut away at 15a, normally abut the ends of the side cutting edges of blade B and grip it sufficiently firmly to make it relatively difficult to cause longitudinal movement thereof. Blade B is frictionally engaged by side walls 19.

Optionally, longitudinal slots may be formed in wall members 16 to facilitate shaving and to aid in cleaning razor R.

Dispensing means of dispenser

Dispenser D is substantially rectangular in shape and is adapted to hold a blade B' in abutment with its top wall and a plurality of blades B'' beneath blade B'. These blades B' and B'' abut each other and are aligned in the direction of the axis of dispenser D. They are held adjacent the rear end wall of dispenser D by means of stop pins 9, which depend from the top wall of said dispenser D. These pins 9 are spaced from the front end wall of dispenser D and check the forward movement of blades B', B''. Blades B', B'' are held vertically in position by means of strip spring 21, which is aligned in the direction of the axis of dispenser D and has a base portion held in a longitudinal trough 22 in the base of said dispenser D. Spring 21 is curved so that it has upper portions 21a near its ends which abut the bottom blade B'' and urge it upwardly.

I provide a slider 25 which is positioned adjacent the undersurface of the top wall of dispenser D. I also provide a groove 24, which extends almost the entire length of said top wall of dispenser D, and a finger piece 26 is located outside said dispenser D, abutting the top thereof. This finger piece 26 is connected to slider 25 by securing means extending vertically through groove 24. Slider 25 extends somewhat in front of finger piece 26 and the member connecting slider 25 to said finger piece 26, so that when finger piece 26 is moved to the rear limit of groove 24, the leading edge of slider 25 extends through slot 23 to the front end of dispenser D.

I also provide a horizontal slot 23 at the top of the rear wall of dispenser D. Slider 25 is no thicker than blade B' and may be moved from the position of Fig. 3, in the direction of the arrow of Fig. 4, to dispense blade B' through said slot 23. Slider 25 is free to pass between pins 9.

Interfitting of dispenser and razor

As stated above, I provide a boss 27 on the rear end wall of dispenser D to serve as wedge means. This boss 27 is slightly narrower than said rear end wall of dispenser D, and the face of boss 27 is slightly rounded. Vertical grooves 29 are formed on each side of boss 27, and a horizontal groove 28 is formed extending across the face of said boss 27.

I provide transverse vertical flanges 14 which respectively project inwardly from the front edges of respective razor walls 19 and preferably extend the entire height of these walls 19. These flanges 14 are respectively notched or grooved at 18 to permit passage of blade B' from slot 23 of dispenser D into blade chamber M, N of razor R.

As is clearly shown in Figs. 1 and 2, when the axis of dispenser D is aligned with the axis of razor R boss 27 is inserted between flanges 14, chamber portions M and N are spread apart. This is because boss 27 is wider than the distance between flanges 14. In the inserted position of Fig. 2, boss 27 separates the front end portions of chambers M and N, and therefore of walls 19, considerably; but the separation gradually decreases rearwardly, and there is little or no separation of the rear end portions of walls 19. Slit 13 assumes a V-shape.

The result of the insertion of boss 27 between flanges 14 is that the front end portions of the side edges of blade B are no longer frictionally engaged by walls 19. In other words, the side edges of blade B are frictionally engaged by walls 19 only at the rear end portion of said side edges. It is therefore easy to insert blade B' and simultaneously eject blade B. However, when blade B' is inserted, it is prevented from falling out until dispenser D is removed from engagement with razor R, because the front portions of the side edges of blade B' are held by walls 19.

When boss 27 is inserted between flanges 14, these flanges 14 respectively lock releasably into place in respective grooves 29. The assembly is properly positioned by means of pins 20, which respectively protrude inwardly from respective walls 19 and are positioned in groove 28 of boss 27.

I also provide horizontal guide flanges 17 which respectively extend inwardly from the top edges of respective walls 19 in front of the front edges of respective wall members 15. When dispenser D and razor R are assembled, these flanges 17 are disposed above the top wall of dispenser D in abutting relationship thereto. The interfitting of pins 20 in groove 28 and of flanges 17 on the top wall of dispenser D control the vertical position of dispenser D in relation to razor R, so that when blade B' is dispensed through slot 23, it will move properly into chamber M, N.

I preferably dimension the parts in such a manner that when dispenser D and razor R are interfitted, slot 23 abuts or very nearly abuts the open end of chamber M, N.

Operation of device

The above-described construction leads to a simple operation of the device to replace a used blade B by a new blade B'.

I grasp razor R in one hand and dispenser D in the other hand and move the rear end of dispenser D adjacent the front end of razor R, as shown in Fig. 1. I then place the top wall 75 of dispenser D in abutment with the under sur-

faces of flanges 17 and slide dispenser D until flanges 14 snap into grooves 29. This position is shown in Figs. 2 and 3.

In this position, as is shown in Fig. 3, finger piece 26 is located at the rear of groove 24, and slider 25 is behind blade B'. I then slide slider 25 forwardly by means of finger piece 26. Fig. 4 shows an intermediate position of slider 25 and shows blade B' entering chamber M, N and pushing blade B out of said chamber M, N. Slider 25 is moved to its extreme forward position, whereby blade B' is completely inserted in chamber M, N, and blade B is completely ejected therefrom.

I then return slider 25 to its original position, as shown in Fig. 5, and remove dispenser D from engagement with razor R. As is shown in Fig. 5, a new blade B'' now abuts the top wall of dispenser D, and is in position to be dispensed therefrom.

I have shown a preferred embodiment of my invention and have indicated certain changes which may be made therein. Various other modifications, additions and omissions may be made in my invention without departing from the scope and spirit thereof.

I have shown a razor blade chamber split into portions M and N, as described. Various spring means may be used to hold these chamber portions M and N together. While I have shown one construction of razor R and dispenser D whereby the latter may be used to wedge chamber portions M and N apart, this construction may be modified to provide other suitable wedge means. Guide means 17 and 20 may be replaced by other suitable guide means, and locking means 14, 29 may be replaced by other suitable locking means.

The above changes, modifications and omissions are not all-inclusive.

I claim:

In combination, a safety-type razor for double-edged blades and a blade dispenser, said razor comprising a blade chamber which is open at each end whereby blades may be inserted and ejected longitudinally therefrom, the upper and

lower walls of said blade chamber respectively having longitudinal slits therein extending the entire length thereof whereby said chamber is divided into two portions, a handle connecting said chamber portions, spring means tensioning said chamber portions toward each other whereby the side cutting edges of a double-edged blade positioned within said blade chamber are frictionally engaged by the side walls of said blade chamber, and dispenser receiving means, said dispenser receiving means comprising respective extensions of the side walls of said blade chamber beyond the transverse walls thereof, the front ends of said wall extensions being turned inwardly to form opposing guide flanges, and opposing pins projecting inwardly from said wall extensions, said dispenser having a leading end portion which is less wide than the dispenser main portion, said dispenser having a transverse slot in the leading end wall thereof and means for ejecting a blade longitudinally through said slot, said leading end wall having a transverse pin groove therein, said leading end portion having transverse locking grooves in the respective side walls thereof, said dispenser and said razor being releasably engageable whereby said locking flanges are respectively positioned in said locking grooves, said pins are positioned in said pin groove, the undersurfaces of said guide flanges abut the top wall of said dispenser, and said dispenser slot abuts an end opening of said blade chamber, said dispenser leading end portion spreading said chamber portions when said dispenser and said razor are releasably engaged.
